United States Patent Office.

JOHN H. FRASER, OF NEW YORK, N. Y.

Design No. 3,299, dated December 29, 1868.

DESIGN FOR A SHOW-CASE.

The Schedule referred to in these Letters Patent and making part of the same.

To all whom it may concern:

Be it known that I, JOHN H. FRASER, of the corner of Reade and Hudson streets, in the city, county, and State of New York, have invented a new and ornamental Design for Show-Cases; and I hereby declare that the said design is correctly represented in the accompanying photographs, which are views of my showcases from opposite ends.

The bottom A, back B, and ends C, may be of common form.

The front, F, is inclined inward at top, where it is connected to the front of the slightly-inclined top, T,

as shown. This imparts to the case a very graceful and ornamental appearance and effect, without material increase of cost.

I claim, and desire to secure by Letters Patent—

The design for a show-case, substantially as herein described.

To the above specification of my invention I have signed my hand, this 3d day of December, 1868.

JOHN H. FRASER.

Witnesses:

JAS. E. CARPENTER,
EDWIN FRASER.
